J. A. LACASSE.
GAME APPARATUS.
APPLICATION FILED JUNE 18, 1917.

1,273,381.

Patented July 23, 1918.

UNITED STATES PATENT OFFICE.

JOSEPH A. LACASSE, OF DETROIT, MICHIGAN.

GAME APPARATUS.

1,273,381.

Specification of Letters Patent. Patented July 23, 1918.

Application filed June 18, 1917. Serial No. 175,290.

To all whom it may concern:

Be it known that I, JOSEPH A. LACASSE, a citizen of the United States of America, residing at Detroit, in the county of Wayne and State of Michigan, have invented certain new and useful Improvements in Game Apparatus, of which the following is a specification, reference being had therein to the accompanying drawings.

10 This invention relates to game apparatus, and has special reference to a miniature checker board, with pawns, that can be conveniently carried in a vest pocket and used by players particularly when traveling.

15 The primary object of my invention is to provide a checker board of the above type with novel means for holding the pawns, whereby the same cannot become accidentally displaced when the checker board is not in use. The pawns are of such construction 20 as to be easily handled and novel means is employed for moving a set of pawns from inactive position to active position so that the pawns may be easily gripped and placed 25 about the checker board.

30 A further object of my invention is to provide a simple, durable and inexpensive checker board and pawns that can be more conveniently used than a large checker board, especially the usual folding box boards, and this and other advantages of my invention will be better understood when referring to the drawing and the detail description thereof.

35 In the drawing,

Figure 1 is a plan of the checker board, showing one set of pawns concealed and the other set of pawns exposed ready to be placed upon the board;

40 Fig. 2 is a cross sectional view, taken on the line II—II of Fig. 1 showing a set of pawns in an inactive position;

Fig. 3 is a similar view showing the pawns in an active position ready to be used;

45 Fig. 4 is a side elevation of the checker board, partly broken away and partly in longitudinal section;

Fig. 5 is a perspective view of a detached pawn elevating member;

50 Fig. 6 is a perspective view of a detached closure or slide, and

Fig. 7 is a perspective view of a pawn.

The checker board is designated 1 and may be made of a plate or block of fiber, hard rubber, glass or any light and durable material that is not materially susceptible to ex-

pansion and contraction. On one side of the plate or block is printed, marked or otherwise indicated the usual number of squares 2 of a checker board and those 60 squares generally used in a checker game are noticeable by pockets 3 in the board. The pockets 3 are cylindrical and approximately half the depth of the board so as to hold the ends of pawns 4.

65 The pawns 4 are cylindrical so that the ends of said pawns may be placed in the pockets 3 of the board. Of course if these pockets are of any other shape, the pawns will be correspondingly shaped and said 70 pawns can be made of metal or any durable material. For instance, one set of pawns may be made of brass and the other pawns from blue steel, so that the two sets of pawns may be distinguishable one from the other, 75 similar to the ordinary black and red checkers. The pawns 4 are approximately the depth of the board, so that when the pawns are placed in the pockets 3, the ends of the 80 pawns will protrude above the face of the board and can be easily gripped and jumped 85 or shifted about the board. An end of each pawn has suitable indicia 5, for instance a circle or cross mark, so that the pawns may be used with the indicia exposed to indicate 90 that the pawn is a "king." It is also possible to provide the ends of all the pawns with indicia that will represent the various pieces of a chess game.

95 The lower face of the board 1, at each end thereof, has a transverse groove 6, and intermediate the ends of said groove the lower face of the board is recessed, as at 7 to provide clearance for a finger. The side walls of the board 1, at the ends thereof, have vertical grooves 8 communicating with the ends of the grooves 6 and in the grooves 6 and 8 are pawn elevating members 9. These members are preferably made from strips of metal bent to provide side arms 10 having 100 inturned ends 11. After the pawn elevating members are placed in the grooves 6 and 8, then the ends of the arms 10 are inturned so as to retain the members in engagement with the board, and yet permit of said members 105 being raised or shifted in the grooves 6 by pressure on said members at the recesses 7, which provides clearance for a finger used to elevate the members.

110 Communicating with the grooves 6 are a plurality of openings 12 disposed in a row and corresponding in number to the pawns.

The openings 12 are adapted to receive the pawns, which rest on the members 9, as shown in Fig. 2, and each set of pawns may be elevated, as shown in Fig. 3, so that the pawns may be placed in the pockets 3 preparatory to a game.

Slidable on the upper face of the checker board at the ends thereof, are slides or closures 13 adapted to close the upper ends of the openings 12 and coöperate with the members 9 in retaining the pawns in the ends of the board. The slides 13 have the ends thereof slotted, as at 14, to receive studs 15 mounted in the board and these studs are adapted to frictionally hold the slides 13 on the upper face of the board, so that after said slides are manually shifted, the slides cannot accidentally shift and release the pawns from the openings 12. The openings 12 not only afford a container for the pawns when the board is not in use but may receive the pawns during a game so that the pawns need not be otherwise held and also preclude loss of the pawns.

I attach considerable importance to the manner in which the pawns are housed in the board and the manner in which the pawns may be elevated to facilitate removal from the board, and while in the drawing there is illustrated a preferred embodiment of my invention, it is to be understood that the structural elements are susceptible to such changes in size, shape and manner of assemblage as fall within the scope of the appended claims.

What I claim is:—

1. A game apparatus comprising a board provided with openings and pawns housed within the openings of said board and adapted to be removed therefrom and used on said board, and means engaging the lower ends of said pawns to elevate said pawns in the openings of said board.

2. A game apparatus comprising a board provided with openings and pockets, pawns normally housed within the openings of said board and adapted to be removed therefrom and placed in the pockets of said board, and means movable in the lower face of said board adapted for elevating the pawns housed in the openings so that said pawns will protrude above said board and may be easily gripped.

3. A game apparatus comprising a board

provided with pockets and openings, pawns housed in the openings of said board and adapted to be removed therefrom and placed in the pockets of said board, elevating members carried by said board and engaging the ends of said pawns in the openings of said board, and means carried by said board adapted for engagement with the other ends of said pawns to retain said pawns on said elevating members and in said board.

4. A game apparatus comprising a board provided with pockets, and openings, pawns normally in the openings of said board and adapted to be transferred to the pockets thereof, elevating members movable in the lower face of said board adapted for shifting the pawns in the openings of said board, and slides on the upper face of said board adapted to coöperate with said elevating members in retaining said pawns in the openings of said board.

5. A game apparatus comprising a board having pockets in the upper face thereof, said board having openings extending therethrough at the ends of said board, pawns normally housed in the openings of said boards and adapted to be transferred to the pockets thereof, elevating members in the lower face of said board adapted for raising the pawns at the openings of said board, and slides on the upper face of said board adapted to be shifted over the openings thereof to coöperate with said elevating members in retaining said pawns in the openings of said board.

6. A game apparatus comprising a checker board having the upper face thereof provided with pockets, said board having openings at the ends thereof, the lower face of said board having grooves communicating with the openings thereof, elevating members shiftable in the grooves of said board, pawns in the openings of said board on said elevating members, and adapted to be raised thereby, and means on the upper face of said board adapted to close the openings thereof to retain said pawns in the openings of said board.

In testimony whereof I affix my signature in the presence of two witnesses.

JOSEPH A. LACASSE.
